DESIGN.

—o—

G. C. VARWIG.

WHISK BROOM HOLDER.

No. 18,374.

Patented June 5, 1888.

UNITED STATES PATENT OFFICE.

GEORGE C. VARWIG, OF PHILADELPHIA, PENNSYLVANIA.

DESIGN FOR A WHISK-BROOM HOLDER.

SPECIFICATION forming part of Design No. 18,374, dated June 5, 1888.

Application filed February 27, 1888. Serial No. 265,522. Term of patent 3½ years.

To all whom it may concern:

Be it known that I, GEORGE C. VARWIG, a citizen of the United States, residing in the city and county of Philadelphia, State of Pennsylvania, have invented and produced a new and original Design for Fronts of Whisk-Broom Holders, of which the following is a specification, reference being had to the accompanying photograph, forming part thereof.

10 The leading feature of my design for the front of a whisk-broom holder consists in its being of the form of a leaf with a border within the edge thereof.

15 A represents the front of a whisk-broom holder, the same being of the form of a leaf, within the edge of which is a border, 1, which

surrounds the main portion 2, said portion being raised or set out from the outer rim or edge, 3. On the front are representations of the veins 4 of a leaf, and at the end thereof is 20 a stem, 5.

I claim—

In a design for a whisk-broom holder, the front thereof, consisting of a main portion, a border, and a surrounding rim, each being of 25 leaf form, the border being within the rim and the main portion raised or set out from the rim, substantially as shown and described.

GEO. C. VARWIG.
